United States Patent Office

Des. 185,233
Patented May 19, 1959

185,233

TRACTOR

William F. H. Purcell, Pasadena, Calif., assignor, by mesne assignments, to Deere & Company, a corporation of Delaware

Application April 25, 1958, Serial No. 50,626

Term of patent 14 years

(Cl. D14—3)

FIG. 1

FIG. 2

Fig. 1 is a three-quarter perspective as seen from the right front of the tractor embodying my new design.

Fig. 2 is a three-quarter perspective as seen from the left front thereof.

Fig. 3 is a front perspective thereof.

Fig. 4 is a three-quarter perspective as seen from the right rear thereof.

Fig. 5 is a side elevation thereof.

The essential features of my design reside in those portions shown in full lines.

I claim:

The ornamental design for a tractor, substantially as shown and described.
